United States Patent

Des. 238,680

Patented Feb. 3, 1976

238,680

OPTICAL SCANNER

Arthur J. Pulos, Fayetteville, and Paul B. Sweeney,
Syracuse, N.Y., assignors to Welch Allyn, Inc.,
Skaneateles Falls, N.Y.

Filed Feb. 4, 1974, Ser. No. 439,269

Term of patent 14 years

Int. Cl. D14—02

U.S. Cl. D26—5 C

FIG. 1

FIG. 2

FIG. 3

FIG. 4

FIG. 5

FIG. 1 is a front elevation of an optical scanner, embodying our new design, the rear elevation being a mirror image thereof;

FIG. 2 is a top plan view thereof;

FIG. 3 is a bottom plan view thereof;

FIG. 4 is a left end elevation thereof; and

FIG. 5 is a right end elevation thereof.

We claim:

The ornamental design for an optical scanner, as shown.
